POWER CRANE, SHOVEL, AND THE LIKE

Leland O. McLean, Mount Lebanon, Pa.

Application March 15, 1934, Serial No. 715,582

3 Claims. (Cl. 212—68)

My invention relates to shovels, cranes, excavating apparatus and the like, and more particularly to such power machines that are in themselves a complete operable unit.

5 The general practice in the design of cranes, shovels, drag lines, trench hoes and similar mechanism is to provide a chassis with a revolving table supported thereon by rollers which is arranged to carry the operator, the boom and 10 the cable-winding apparatus.

In the stationary power plant type of machine the motor is carried by the chassis in the rear of the revolving table and the operating power and some of the controls for the boom and 15 its associated parts are transmitted from the motor to the apparatus on the revolving table through the center thereof. When the operator wishes to maneuver this type of machine he is required to turn from the controls of his normal 20 working position to operate the necessary levers on the chassis. Thus moving or turning of the whole machine involves a considerable loss of operating time. Again it is difficult to load and impossible to dig at the rear of this shovel, as the 25 stationary motor is in the way, which is an undesirable feature of this type of machine.

The other general type of machine is known as the full revolving machine. The power plant of this type of machine is on the revolving table 30 and the locomotive power is transmitted down through its pivotal axis to the chassis and the driving mechanism. The revolving table in this type of machine is ordinarily rectangular in shape, the axis of rotation not being at the center but approximately one-fourth of the length 35 of the table from the forward end thereof.

The motor is located on the rear end of the table so that its weight helps to counterbalance the boom mechanism. When the table is rotated 40 the rear end swings out over the chassis and the propelling mechanism. This feature is termed the "tail swing" of the machine.

Tail swing is a very undesirable feature especially if the operator of the shovel does not have 45 full vision from his cab. He is unable to work in narrow or confined places owing to the large clearance required for the rear of his machine which might strike objects such as the trucks being loaded or the side of the narrow cut. Men 50 working behind a shovel have often been crushed between the tail of the machine and a fixed object as the operator did not have full vision around his machine and could not control the tail swing without a great loss of time.

55 One object of my invention is to provide a

crane, shovel or similar mechanism that is full revolving and does not have any parts projecting beyond the propelling base.

I attain this purpose by providing the machine with a rotary table arranged to carry the power plant, the hoisting mechanism, and the operator, which table does not extend beyond the propelling base regardless of the position it may be in.

This improvement is made possible by the arrangement and design of the parts of the machine and which lower the center of gravity of 10 table assembly.

I attain this feature by eliminating the ordinary 15 table rollers thus lowering the center of gravity of the machine and rendering it more stable obviating the necessity of counterbalancing the boom mechanism by a weight which would have to extend a considerable distance from the center of rotation of the table.

To this purpose I employ a plurality of novel 20 hook rollers adapted to operate in a horizontal groove or channel in the base of the mechanism and arranged to rotatably support the table against working thrusts, preventing it from tilting with respect to the base casting.

The hook rollers which support the table on the 25 base casting are disposed in the same substantially horizontal plane as the central spindle bearing of the table.

This improved feature has a number of unique 30 advantages.

The hook rollers relieve the central bearing of 35 all bending stresses. The track in which the rollers ride has inwardly converging walls and the rollers are tapered or frustro-conical, so that by 40 properly adjusting the rollers axially the table is effectually prevented from tipping. The location of the hook rollers in the same plane as that of the central bearing makes possible the relief 45 of the central bearing from bending stresses and eliminates the tendency to table tipping during the operation of the machine.

The feature of lower center of gravity of the 50 table mechanism, which permits the mounting of the power plant on a table and eliminates tail swing, also permits full vision of the operator 55 around the shovel so that he may quickly and advantageously operate the machine, something which has not been practical heretofore on a full revolving shovel.

Again, the turntable is supported closely adjacent to the base casting which permits the use of a short heavy spindle or stub shaft for centering the turntable, making the mechanism 55 stronger and more rigid.

This feature also permits the use of a short vertical swing shaft which eliminates the tendency for the swing shaft pinion to bind in the circle gear track.

5 All of these features are not attainable on the present design of full revolving machines of this nature because of the difference in the elevation of the supporting rollers and the spindle or stub shaft mechanism.

10 A further object of my invention is the provision of a combination crowding mechanism which is efficient and universal in its use on a shovel mechanism.

To complete the efficiency of operating the 15 machine to the best advantage of the novel features therein I provide a pneumatic trip for the dipper bottom controlled by the control levers making up a control system which is novel in my machine.

20 Other objects, and also other novel features of construction, and also of arrangement of parts, will appear from the following description.

In the accompanying drawings, wherein I have illustrated a practical embodiment of the principles of my invention, Fig. 1 is a side elevation 25 partly in section illustrating some of the novel features of my invention.

Fig. 2 is a plan view of the same with the housing and cab cut away to show parts.

30 Fig. 3 is an end view from the rear with the power plant removed and the housing and cab in section.

Figs. 4 and 5 are sectional views on enlarged scale showing in detail the structure of the hook 35 rollers and their associated parts.

Fig. 6 is a side elevation showing the boom assembly.

Fig. 7 is a sectional view of the shipper shaft mechanism taken on the line 7—7 of Fig. 6.

40 Fig. 8 is a sectional view of the pneumatic tripper drum mechanism and its associated parts taken on the line 8—8 of Fig. 6.

Fig. 9 is a plan view of the turntable, parts of which are broken away, showing a modification 45 of the shaft assembly.

Fig. 10 is a side elevation looking from the right in Fig. 9.

Fig. 11 is a side elevation, partly in section, looking from the left in Fig. 9.

50 Referring to the drawings, 10 represents a standard propelling base or crawler mechanism consisting of the frames 11 which extend longitudinally of the crawler mechanism and are arranged to rotatably support the crawler link belts 55 12 by means of the end driving sprocket gears 13 and the opposite end idler sprockets 14.

The under sides of the frames are provided with a series of idler load-carrying rollers 15 which are arranged to ride on the interior of the 60 crawler belt 12 as it passes beneath the frame between the end sprockets, thus carrying the load of the mechanism. The top idler rollers 16 are provided to carry the weight of the crawler belt 12 and prevent it from sagging between the end 65 sprockets.

The alined shafts 17 support the belt-driving sprockets 13 and are provided with the chain sprockets 18.

The frames 11 of the propelling base are rigidly 70 connected by the cross beams or members 19 which are arranged to carry the entire shovel mechanism.

20 represents a base casting, generally known as a "circle gear and roller track casting", 75 and which is provided with the depending legs 21

arranged to be secured to the beams 19 by means of the bolts 22. The circular perimetral surface of the base casting is provided with an annular groove or channel track 23, the upper and lower surfaces or sides 24 and 24' of which converge 5 inwardly to receive a conical roller.

25 represents an internal annular gear track cut on the upper internal face of the casting and arranged to receive a rotating pinion. The base casting 20 is provided with the radial spokes 26 10 terminating in the hollow hub or spindle 27, said spokes being below the gear track, as shown in Fig. 3.

28 represents a pair of brackets depending from the casting 20 at each side thereof and arranged 15 to support the housing of the lower horizontal propelling shaft mechanism. The outer ends of the propelling shafts are provided with the chain sprocket gears 29 arranged for driving the sprocket gears 13 of the propelling base by means of 20 the chains 30.

The propelling shafts are provided with the brakes 31, inwardly adjacent to the brackets 28, which brakes are arranged to be separately operated to prevent the rotation of either or both 25 of the propelling shafts for steering the machine when traveling or for locking both propelling shafts to prevent movement of the propelling base.

32 represents the differential housing arranged for carrying the differential mechanism 30 of the lower horizontal propelling shafts. The differential housing 32 is secured to the under side of the base casting 20 at the center thereof. The differential mechanism is of a design similar to those used on motor vehicles and is not 35 therefore shown in detail. The beveled pinion of the differential is secured to the lower end of the tubular drive shaft 33.

The drive shaft 33 is hollowed to permit the passage of a plurality of coaxially arranged air 40 lines (not shown) therethrough for operating the pneumatic brakes 31 or other means for operating the brakes.

The drive shaft 33 extends up through the spindle 27 and is supported therein at its upper 45 end by the antifriction bearings 34.

35 represents a circular revolving table of the shovel mechanism which is arranged to carry the power plant and all the mechanism and controls for operating the shovel. The center of the 50 under side of the revolving table is provided with the hub 36 having the bearing bushing 36' which is arranged to rotatably engage the exterior surface of the spindle 27, thereby maintaining the table on its centered pivoted connection. The hub 36 is adequately strengthened or braced by the radial ribs 37 which terminate in the annular depending flange member 38 of the rotary table.

39 represents an end plate secured to the upper 60 surface of the center of the table and which is arranged to carry the end thrust bearing of the beveled pinion 40 secured on the upper end of the drive shaft 33. 41 represents a pressure grease fitting screwed into the plate 39 for admitting lubricant to the bearing 34.

The rotary table 35 is supported by a plurality of oppositely disposed and arcuately arranged tapered or conical rollers 42 which ride in the track 23 and are arranged to engage the surfaces 70 24 and 24' thereof. The term "channel track" is employed to indicate a track having upper and lower engaging surfaces. Said rollers are rotatably supported by means of the brackets 43 depending from the table 35 and radially adjust- 75

able therewith. The brackets may be provided with a horizontal T-shaped portion as at 44 arranged to slide in a complementary T-shaped slot 45 in the box-like structure 46 which may be integral with or secured in any suitable manner to the underside of the table 35. The underside of the box has fastened thereto the back-up plate 47 as by the bolts 48, which plate is arranged to clamp and receive with the T-shaped slot of the box any upward thrusts from the brackets 43. The table is slotted as at 49 to receive the bolts 50 which screw into and lock the brackets 43 in position after they have been adjusted in the annular groove 23.

15 51 represents lugs depending from the table 35 at a point radially beyond the brackets 43 and the box structure 46. These lugs are provided with threaded holes for receiving the radial adjusting screws 52. The inner end of the adjusting screws 52 are arranged to move the brackets 43 radially and are provided with lock nuts to hold them in place after the adjustment is made.

20 The depending portion 53 of the brackets 43 is provided with the non-rotatable shaft 54 which carries the conical rollers 42 on the anti-friction bearings 55. Fig. 2 of the drawings shows the preferred arrangement of these supporting rollers and their radial adjusting mechanism wherein four rollers are each radially positioned about the table at an angle of approximately twenty degrees from a plane bisecting the circular table and the boom of the shovel. When the shovel is working or digging the fore rollers support the downward thrust by riding on the lower side 24' of the track 23 while the aft rollers take the upward thrust, or vice versa when the thrusts are reversed, thus relieving the spindle 27 from bending strains. Therefore the revolving table is rotatably supported by the rollers 42 and the conventional turntable rollers which in common practice are interposed between the base casting and the turntable are eliminated.

25 It will be noted that the construction described enables the center bearing of the turntable to be lowered so that the plane of the axes of the rollers 42 will intersect said bearing, thus reducing the bending stresses effective on the spindle 27 to a minimum.

30 56 represents the motor or power plant which is secured on the rear of the table and transversely thereof. The radiator 57 and the crank 58 extend beyond the covering or hood 59. The other end of the motor is provided with the transmission as indicated at 60 which has the usual gear shifting lever and clutch mechanism (not shown).

35 The drive shaft 61 extends beyond the transmission 60 and is provided with the sprocket gear 62 which rotates counterclockwise in Fig. 1, and is arranged to drive the sprocket gear 63 of the first intermediate drive shaft 64 by the chain 65. The shaft 64 is journaled in suitable bearings on the table 35. The sprocket gear 62 is 40 of smaller diameter than the sprocket gear 63 and effects a reduction in speed of the first intermediate driven shaft 64.

45 The shaft 64 is provided with the multiple belt drive pulley 66 arranged to drive the air compressor 67 mounted on the table 35, by means of the belt 68.

50 69 represents a sprocket gear on the shaft 64 for driving, through the medium of the chain 70, the sprocket gears 71, 72, and 73 of the upper horizontal propelling shaft 74, the horizontal

swing shaft 75, and the main hoisting shaft 76, respectively, all of which shafts are arranged transversely of the table 35. These shafts rotate clockwise, counterclockwise and counterclockwise, respectively, in Fig. 1, and are journaled in the frame members 77.

55 The frame members 77 are provided with the inwardly and oppositely disposed flange members 77' arranged to support brake band mechanism applicable to operate on the drum mechanisms carried by the shaft 76.

60 The upper horizontal propelling shaft 74 is positioned directly over the center of the table 35 and rotatably carries the beveled gear 78 arranged to mesh with the pinion 40 on the upper end of the shaft 33. Upon engaging the mechanical clutch 79, fixed to the shaft 74, with its complementary part in the beveled gear 78, power may be transmitted from the shaft 74 to the shaft 33 and the differential mechanism, thereby operating the lower horizontal propelling shafts for driving the sprocket gears of the crawlers to effect propulsion of the mechanism. The direction of travel of the crawlers may be effected by the shifting of the usual gears in transmission 60.

65 The rotary shaft 74 is also employed as second intermediate drive shaft for operating the boom hoist drum 80. This is effected by engaging the mechanical clutch 81, fixed to the shaft 74, with its complementary part in the beveled gear 82 rotatably mounted on the shaft 74 and which meshes with the beveled pinion 83 keyed to one end of the inclined shaft 84 suitably journaled from the table 35. The other end of the shaft 84 is provided with a worm pinion 85 in mesh with the worm gear 86 on the horizontal boom hoist shaft 87 which carries the drum 80 and is journaled on the underside of the table 35. The drum 80 is provided with the cable 88 which is employed to raise and lower the boom and extends up through the table 35. Since the boom hoist drive mechanism includes a meshing worm pinion and gear it is necessary that it be positively driven in both directions. This movement is accomplished by shifting the gears in the transmission 60 as in the case of reversing the direction of the propulsion crawlers.

70 89 represents a sprocket rotatably mounted on the shaft 74 and which may be caused to rotate therewith by engaging the pneumatic clutch 90, the latter being operable by means of the air ram 91. The sprocket 89 is arranged to drive the sprocket 92 mounted on the crowd spool 93 by means of the chain 94. The spool 93 is rotatably mounted on the shaft 76 but may be caused to rotate with said shaft by energizing the pneumatic ram 91 to engage the clutch 90.

75 The horizontal swing shaft 75 is provided with the opposed air rams 95 and 96 which operate respectively the clutches 97 and 98 for driving the beveled pinions 99 and 100 which are in continuous engagement with the beveled gear 101. The beveled gear 101 is secured to the upper end of the vertical swing shaft 102 which is journaled in the table 35 and has secured at its lower end the pinion 103 arranged to mesh with the internal gear track 25 in the stationary base casting 20. Thus by energizing the pneumatic ram 95 and closing the clutch 97 the beveled pinion 99 will drive the beveled gear 101 counterclockwise in Fig. 2, thereby swinging the table 35 clockwise in Fig. 2. Similarly if the pneumatic ram 96 is energized the table 35 is caused to rotate counterclockwise.

The pneumatic rams 95 and 96 are controlled by operating a single lever in opposite directions so that only one ram may be energized at a time.

Referring now to the main hoist drum shaft 76, which is at the apex of the operating shaft assembly, 104 represents a pneumatic ram arranged to operate the clutch 105 which imparts rotary movement to the main hoist drum 106 rotatably mounted on the shaft 76 for winding the hoist cable 107 thereon.

108 represents a pneumatic ram arranged to operate the clutch 109 for driving the crowd spool 93 in a counterclockwise direction in Fig. 1 on the shaft 76. Thus by means of the clutch 90 15 the crowd spool 93 may be rotated in a clockwise direction in Fig. 1, while by means of the clutch 109 a reverse rotation of the crowd spool may be effected.

The spool 93 is provided with the sprocket 110 20 arranged to drive the sprocket 111 by means of the chain 112. The sprocket 111 is fixed to the sleeve 113 which is rotatably mounted on the stationary boom hinge pin 114. It is obvious that the direction of rotation of the sprocket 111 is 25 determined by the selective energization of the pneumatic rams 91 and 108 which are controlled by a single lever operated in opposite directions as previously explained.

115 and 116 represent air pistons mounted on 30 the brackets 77 and which are arranged to operate the brake bands 117 and 118 of the main hoist drum 106 and the crowd spool 93 respectively. These brake bands are arranged to retard the movement of their respective drum and 35 spool or to lock the same against movement.

The stationary boom hinge pin 114 is supported on the table 35 and in the front thereof by means of the upstanding lugs 119. The ends of the pin 114 carry the base sockets 120 arranged to receive 40 the compression or front legs 121 of the boom hoist mast 122. The table 35 is provided with the upstanding lugs 123 between which is attached the lower end of the tension or rear leg 124 of the mast 122. The three legs of the mast 45 122 converge at their upper ends in the mast head 125 which is usually provided with a pair of idler pulleys or sheaves 126 arranged to carry the boom hoist cable 88 which starts from the boom hoist drum 89 and passes over one of the mast sheaves 50 126 to a pulley at the outer end of the boom and returns to dead end the other mast sheave 126 as shown in Fig. 1.

127 represents a box type boom whose inner end is provided with the boom base castings 128 55 which are hingedly attached as at 129 to the boom hinge pin 114 between the lugs 119. The other end of the boom is provided with the boom cap casting 130 for supporting the idler boom hoist sheave 131 and the main hoist sheaves 132. The 60 former carries the boom hoist cable 88 while the latter sheaves carry the main hoist cable 107.

Intermediate of its ends and on the upper surface thereof the boom has adjustably secured thereto the shipper shaft assembly 134, a sectional view of which is shown in Fig. 7. This assembly 65 includes a shaft 135 journaled in the bearings 136 secured to the upper surface of the boom. The pinions 137 which are secured to the shaft 135 on each side of the boom movably support the dipper sticks or handles 138 whose under sides are provided with the racks 139 arranged to mesh with and be driven by the pinions 137. The outer ends of the shaft 135 rotatably support the brackets or guides 140 in which the dipper sticks slide and 70 75 which extend up along the outer sides of the

sticks and project inwardly over the top and ride upon the upper surface thereof.

141 represents a spool or cable drum keyed to the middle of the shaft 135 between the bearings 136. The boom is cut away to receive the flanges 142 and 143 of the drum 141. The perimeter of the flange 143 is provided with sprocket teeth to receive the crowd chain 144 which is driven by the sprocket 145 secured to the sleeve 113 on the hinge pin 114.

Thus the dipper sticks 138 may be moved in by energizing the pneumatic ram 108 which engages the clutch 109, driving the crowd spool 93 counterclockwise in Fig. 1, thereby driving the chain 112, the sprocket 111, the sleeve 113, the sprocket 145, the chain 114, causing the shipper shaft 135 to move the dipper towards the boom. Again if the pneumatic ram 91 be energized to engage the clutch 90 for driving the sprocket 89 from the shaft 74 thereby rotating the crowd 20 spool 93 in the opposite or clockwise direction, the dipper is moved out or away from the boom. The pneumatic rams 91 and 108 are operated by the movement of a control lever in opposite directions. Thus it is impossible to create an interference between these movements by energizing both rams simultaneously.

The outer end of the dipper sticks 138 are connected by the casting 138' to which is hinged the dipper, shovel or bucket 146 which is provided 30 with the dipper hoisting block assembly 147 arranged to receive the hoisting cable 107.

The outer or remote end of the hoisting cable is attached to the drum 141 of the shipper shaft assembly and is wound several times therearound. 35 The cable is then carried over one of the sheaves or idler pulleys 132 in the boom cap casting, thence to the dipper hoisting block assembly 147 and back to the other sheave 132 of the boom cap casting and thence to the main hoisting drum 40 106. Thus if the crowd chain assembly is permitted to freely rotate by releasing the brake 118 on the crowd spool 43 the hoist cable 107 may be used for crowding out the dipper. The weight of the dipper at the end of the dipper sticks is 45 then sufficient to cause the dipper to drop unreeling the hoist cable that is wound around the shipper shaft drum 141. During this action the main hoist drum 106 is locked so the movement of the dipper is out and slightly downward. Before 50 the sticks are run completely out the main hoist drum is released and the cable 107 is permitted to unreel therefrom. The dipper would then swing in an arc back towards the base of the boom and in the position to dig, the sticks being almost 55 all the way out. The pneumatic ram 104 is then energized, which actuates the clutch 105, causing the main hoist drum 106 to reel-in the hoisting cable 107. The weight and the resistance to movement of the material scooped up by the dipper is then divided into two forces by the pull on the hoist cable 107. Part of the energy will be used in pulling the dipper forwardly and the rest will be used in unreeling the cable 107 from the shipper shaft drum 141 which forces the 60 dipper sticks away from the boom, causing the dipper to crowd further into the soil or material to be removed. When the resistance of the material to the downward movement of the dipper becomes greater than the resistance of the material to the forward pull on the dipper the cable 107 will stop unreeling on the drum 141 and the dipper will be raised as it is drawn forwardly. When the resistance to the downward movement of the dipper becomes less, the sticks tend to 70 75

crowd the dipper down to equalize the load until the sticks are all the way out. This is termed the "cable crowd out", and is very successful because of its uniformly efficient method of digging.

5 The other method for crowding out is by means of a positive drive, as by driving out the dipper sticks by rotating the chain 144 in a clockwise movement in Fig. 4 as previously described. This method is not as efficient as the "rope crowd" as 10 the operator must divide the power between the hoisting and crowding out actions at the operating shaft mechanism, and the result is that he is never able to balance the loads as automatically occurs with the "rope crowd" method.

15 However the positive chain crowd is more satisfactory to draw the dipper sticks in and I have therefore employed the best features of both methods to obtain what I term as a "rope-chain crowd" and the rope crowd feature must necessarily employ the chain crown-in feature to obtain a complete crowd function.

To complete the operation of digging with a shovel I have provided the dipper with a pneumatic tripper mechanism for releasing the door 25 of the dipper to permit the material to fall therefrom. Referring especially to Fig. 8 to accomplish this function I employ a reel 148 journaled on the hollow shaft 149 fixed within the boom 127 above the shipper shaft mechanism. Compressed 30 air is fed from the table 35 to the shaft 149 by the tubing 150 which is connected therewith so as to open into the hollow portion 151 of the shaft 149. The shaft 149 is provided with the ports 152 which form a communication between the hollow portion 35 151 of the shaft and the annular recess 153 in the bore of the reel 148 which in turn is provided with a hose connection as shown at 154. The recess 153 is properly sealed against the escape of air by the annular sealing rings 155 and 40 is provided with adequate lubricating appliances.

156 represents a helical spring secured at one end to the boom and at the other end to the reel 148. This permits the unreeling of the hose 157 from the reel as the dipper is moved out from the boom 45 and draws the hose back onto the reel as the dipper is retracted.

158 represents two pulleys mounted in the under side of the boom for guiding the hose 157 therethrough.

50 The other end of the hose terminates at the box 159 mounted on the rear of the casting 138' and arranged to house the piston 160 which is provided with a spring to maintain it in its retracted position. When the compressed air is admitted 55 to the tubing 150 it travels through the recess 153 of the reel and the hose 157 and forces the piston 160 against the lever 161 which rocks on its fulcrum 162, causing the other end thereof to strike the flanged head of the sliding bolt 163 releasing the bolt from the lock slot 164 of the dipper. The door of the dipper then swings away on its hinges 165 pivoted at 166 and the material falls from the dipper. As the dipper is returned to the 60 position for scooping more material the weight of the door is sufficient to permit it to close and become locked by the bolt 163 which slides into place by means of its own weight.

The housing 59 incloses not only the motor but 70 also the horizontal shafts 74, 75 and 76 and associated mechanism being apertured to provide clearance for the extension of parts therethrough. At the side, the right in Fig. 3, it is stepped down to form the floor of the cab 59' in which the operator sits or stands. The upper walls of the cab are

provided with windows so that the operator has a clear vision in all directions.

167 represents the chain crowd and swing control lever within the cab, which actuates pneumatic valves to energize the respective rams for operating the clutches to engage the selected crowd and swing parts of the mechanism. Forward movement of the lever operates the dipper to crowd-out and the rearward movement operates the pull-in of the dipper; while movement of the lever to the left causes the turntable to rotate counterclockwise swinging the boom to the left and movement of the lever to the right swinging the boom to the right. When the lever is in its neutral position with respect to the crowd function the crowd brake 118 is automatically applied.

168 represents the main hoist drum and trip control lever also in the cab. By moving this lever forward the brake 117 of the main hoist drum 106 is released and the weight of the dipper is permitted to unreel the cable therefrom. Moving this lever to the rear operates the ram 104 to reel in the cable 107, and moving it right operates the trip mechanism. The operator thus has full control of the digging operations of the machine 25 through the medium of two small universal levers.

The levers 167 and 168 may conveniently be of the general type disclosed in my Letters Patent No. 1,711,896, issued May 7, 1929.

30 Referring to Figs. 9 to 11, inclusive, I illustrate the practical embodiments of my invention as a modification thereof. The parts similar to those discussed above are being designated by the same reference numerals.

35 170 represents the upper horizontal drive shaft journaled in the bearings 171 and 172, and 173 represents the main hoist drum shaft journaled in the bearings 174 and 175. These shafts are driven from the first intermediate shaft 64 by 40 means of the sprocket 69, by the chain 70 and the sprockets 72 and 71 on shafts 173 and 170, respectively.

As shown in Fig. 10, the chain 70 runs around the sprocket 72 of the shaft 173, rotating said 45 shaft in a counterclockwise direction, and meshes with the sprocket 71 from below, rotating the shaft 170 in a clockwise direction.

The shaft 170 is provided with the beveled gear 78 arranged to mesh with the pinion 40 for propelling the machine when the toothed clutch member 176 is moved to the left. Moving the clutch 176 to the right drives the beveled gear 82 which is meshed with the beveled pinion 83 on the inclined shaft 84 for driving the boom hoist 55 drum 80, on the shaft 87 through the meshed worm and gear 85 and 86.

The shaft 170 is provided as before with the chain crowd-out mechanism, which comprises the pneumatic ram 91 for operating the clutch 90 to 60 drive the sprocket 92 and the crowd spool 93 in a clockwise direction.

65 On the other side of the bearing 171, the shaft 170 is provided with the sprocket 171 which may be made to rotate with the shaft by energizing the pneumatic ram 178 for operating the clutch 179. The sprocket 171 drives the chain 180 in a counterclockwise direction in Fig. 11, which in turn drives the sprocket 181 fixed to the horizontal swing shaft 182 journaled in the bearings 183. 70 One end of the horizontal swing shaft has fixed thereto the beveled pinion 100 which meshes with the beveled gear 101 secured to the upper end of the vertical swing shaft 102. Thus the clutch 179 on the shaft 170 operates the vertical 75

swing shaft 102 in a clockwise direction in Fig. 9, revolving the table 35 to the left or counter-clockwise.

Similarly, the shaft 173 is provided with the 5 pneumatic ram 184 arranged to operate the clutch 185 to rotate the sprocket 186 in a clockwise direction in Fig. 11, thus driving the chain 180, the sprocket 181, the horizontal swing shaft 182, and the beveled pinion 100 in a counter-clockwise direction. The vertical swing shaft 102 is thereby rotated in a counter-clockwise direction in Fig. 9 and the table 35 swung to the right.

The rams 178 and 184 are supported by the brackets 187 which may be bolted or otherwise 15 fastened to the table floor. The other rams, 91, 104 and 108 are fastened to the bearings 171, 175 and 174, respectively.

The main hoist drum 106 and its operating 20 mechanism is the same as that described above except that it is in the reversed position on the shaft 173.

The crowd spool 93 and the crowd-in mechanism is also the same as before except that it 25 is mounted on the opposite side of the main hoist drum shaft.

The reversal of these parts is due to the provision of the single clutch member 176 which is employed, when moved to the left, to propel the 30 mechanism and is arranged to lower or raise the boom when moved to the right.

The modification illustrates a novel method 35 of reducing the shaft assembly to an arrangement in a substantially single plane which provides for better vision for the operator and lowers the center of gravity of the machine.

Fig. 11 also shows a modification in the manner 40 in which the turn-table 35 is journaled to the base casting 20. 188 represents a hollow stub shaft integral with the table 35 and arranged to be journaled in vertical bearing 189 held by the hub 190 of the base casting 20. The spokes, or ribs, 26 are arranged to support the hub 190 and provide reinforcement for the base casting 20. The internal bearing surface of the bearing 45 189 may be convex, its walls converging slightly inwardly from the ends to a circle or zone in the center thereof. This zone is in the same plane as the axes of the supporting rollers 42. If the table is tipped slightly due to the required 50 clearance of the rollers 42 in the annular track 23, the stub shaft 188 will roll about an imaginary horizontal axis, on the internal convex surface of the bearing 189 and thus avoid transmission of any bending strains to the hub 190 of the base 55 casting 20.

The channel track and hook roller construction, provide the important features of my invention, together with the mono-plane table supporting feature which permits the lowering of the center of gravity of the turn-table and the mechanism mounted thereon, eliminating the use 60 of the ordinary turn-table supporting rollers and the long spindles for centering the turn-table.

This invention permits the use of a power plant mounted on a circular turn-table, no part of which extends beyond the rim of the table but all within the spread of the ordinary crawler propelling base. Heretofore this feature was impractical, as the supporting rollers for the rotary table positioned the turn-table considerably above the ring gear casting, requiring an extended spindle which was subject to breaking stresses if the boom were not counterweighted by a weight 10 or portion of the apparatus extended from the spindle to form a lever arm much greater than that of the boom. This feature necessitated considerable tail swing.

My invention permits the assembly of the 15 rotary table in close relation to the ring gear, which eliminates the strains on the spindle and drops the center of gravity, increasing the efficiency of the machine very materially and eliminating any tail swing whatsoever. 20

I claim:

1. The combination with a base member, an annular exterior channel track carried by said base member, a turntable member, a plurality of rollers carried by said turntable and engaging said 25 track for supporting the turntable, of universal bearing means between said members to maintain them in coaxial relation, said bearing means comprising a vertically disposed arcuate bearing surface, the center of the closed-curve 30 contact between the bearing surface being disposed in the plane of the axes of said rollers.

2. The combination with a base member, an annular exterior channel track carried by said 35 base member, a turntable member, a plurality of rollers carried by said turntable and engaging said track for supporting the turntable, of a central bearing element on one of said members, a central stub-shaft on the other of said members arranged to be inserted in the bearing element, 40 an arcuate bearing surface interposed between the bearing element and the stub-shaft to provide for universal movement therebetween, the axes of said rollers being in a plane that intersects the center of the circular-line contact 45 between said arcuate bearing element and said stub-shaft.

3. The combination with a dirigible chassis, a base member mounted on the chassis, an annular 50 channel track carried by said base member, a turntable member, a plurality of rollers carried by said turntable and engaging said track for supporting said turntable, of universal bearing means between said members to maintain them in coaxial relation, said bearing means comprising a 55 vertically disposed arcuate bearing surface, the center of the closed-curve contact between the bearing surfaces being disposed in the plane of the axis of the rollers, said bearing means being hollow to provide for the passage of means for 60 guiding and propelling the chassis.

LELAND O. MCLEAN.
